UNITED STATES PATENT OFFICE

GEORGE L. RICHARDSON, OF SAN FRANCISCO, CALIFORNIA

DESIGN FOR A LIGHT STANDARD

Application filed April 18, 1930. Serial No. 35,305. Term of patent 3½ years.

To all whom it may concern:

Be it known that I, GEORGE L. RICHARDSON, a citizen of the United States, residing at San Francisco, in the county of San Francisco and State of California, have invented a new, original, and ornamental Design for a Light Standard, of which the following is a specification, reference being had to the accompanying drawing, forming part thereof,

in which Figure 1 is a side elevation of my light standard, Figure 2 a vertical section through the lower portion of the standard, and Figure 3 a horizontal section taken along line 3—3 of Figure 2.

I claim:

The ornamental design for a light standard as shown.

GEORGE L. RICHARDSON.
